By William James, A.M.

UNITED STATES PATENT OFFICE

JOSEPH SUNNEN, OF ST. LOUIS, MISSOURI

PORTABLE GRINDER STAND

Application filed June 27, 1930. Serial No. 464,179.

This invention relates to portable stands for cylinder grinders, electric portable drills, and the like.

The present invention is particularly adapted for use for supporting portable electric drills used to operate cylinder grinders or honing machines, such as disclosed in my co-pending applications.

This type of grinder is especially used to 10 grind or refinish cylinders of internal combustion engines. When in use the operating spindle of the grinder is attached to the chuck of the electric drill and the grinder is operatively supported thereby. During the operation of the grinder the electric drill is raised and lowered so as to impart to said grinder reciprocating or longitudinal movement axially of the cylinder surfaces.

As the combined weight of the drill and 20 the grinder is considerable, it is readily apparent that unless a suitable support is provided, the workman will be hampered in his work by the excessive weight of the operating unit and will not be able to work in an efficient 25 manner.

The object of the present invention is to provide a support which efficiently supports the drill and grinder in proper position with respect to the cylinder so that the workman 30 is relieved of supporting the operating unit and is merely called upon to guide the same and cause reciprocating movement of the grinder axially within the cylinder.

Further objects of the invention are to provide a support of the class described having a standard provided with a base by means of which said standard can be firmly attached 35 in proper position to the cylinder block, the upper end of said standard being provided with a lateral arm which is adjustable about the axis of said standard, whereby the grinder can be moved from one cylinder to the other.

Other objects of the invention are to provide a support of the class described having an adjustable base adapted to be inserted into a supporting position within a cylinder and which base is adjustable for different sized 45 cylinders.

Still further objects of the invention are

to provide a grinder stand of the class described having an expandable base which, when placed in the cylinder, is automatically expanded so as to support the stand in position, and including supporting means suspended in position and adapted to engage a portable drill and support it and the grinder in proper operative position, there being spring means provided to permit vertical reciprocating movement of the operating unit, 55 said spring means being adjustable to compensate for difference in weight of drills.

Additional objects of the invention are to provide a standard having an expandable foot or base which, when placed in a cylinder, is automatically expanded therein by the weight of the standard so as to hold the latter in proper position, the upper end of said standard being provided with a swivel arm from 60 which the drill and grinder are suspended, 65 said arm being adjustable about the axis of said standard so that cylinders on both sides of the stand can be ground with one setting, and to provide means for locking the expansion foot rigidly in the cylinder.

With these and other objects in view, my invention consists in certain novel features of construction and arrangement of parts, hereinafter more fully described and claimed, 70 and illustrated in the accompanying drawings, in which—

Figure 1 is an elevational view of my stand showing it in position in a cylinder.

Figure 2 is an enlarged detail view, partly 75 in cross section, of the base or expansion foot of the stand and showing it in retracted position.

Figure 3 is an enlarged vertical cross section of the upper end of the stand and showing 80 the swivel arm partly broken away.

Figure 4 is a horizontal cross section taken on line 4—4 of Figure 3.

Figure 5 is an enlarged cross section taken on line 5—5 of Figure 1.

Figure 6 is an enlarged cross section taken on line 6—6 of Figure 1.

Figure 7 is an enlarged horizontal cross section taken on line 7—7 of Figure 1.

Referring by numerals to the accompanying drawings, 10 indicates a standard, 11 an

arm extending laterally from the upper end thereof, and 12 means suspended from said arm and supporting, by a strap A, a portable electric drill B to which is operatively attached a cylinder grinder C. This grinder is normally disposed above a cylinder block D and is so supported that it can be moved into the cylinder which it is desired to refinish or hone. The electric drill is of any standard construction and the grinder is preferably of the type disclosed in the before-mentioned application.

The standard 10 consists of a tubular member 14 of suitable length and having its lower end provided with a base 15 and an expansion foot or member 16. Base 15 consists of a pair of channel members 17 spaced from each other and having their upper ends converging and secured to the lower end of tubular member 14. The lower portions of members 17 are secured in spaced-apart relation by a plurality of pins or transverse rods 18 which have their ends secured in said members. Pivotally mounted on each pin 18 are the rear ends 19^a of a pair of links 19, the forward ends of which are pivotally secured to expansion member 16 as indicated at 20.

Member 16 is preferably T-shape in cross section with the web portion 16^a presented toward base 15 and with the ends of links 19 arranged on each side of said web portion. The upper end of flanged portion 16^b is bent outwardly and downwardly to provide a hook 21 by means of which said expansion member 16 can be hooked over the top of the partition wall separating two cylinders (see Figure 1).

Links 19 are of sufficient lengths so that even when said expansion foot occupies its outermost position the pivotal connections 20 of said links are disposed below the horizontal planes of the respective pins 18. When the expansion member 16 is retracted it occupies a lower position as shown in Figure 2. A coiled spring 22 is preferably arranged on each pin 18 and serves to hold the corresponding ends of links 19 in spaced-apart relation.

Tubular member 14 is of suitable length and the upper end thereof is seated in a cap member 24, the upper end of which is apertured as indicated at 25. A rod 26 is slidably disposed in tubular member 14 and extends beyond the ends thereof, the upper end being threaded as indicated at 26^a and extending upwardly a suitable distance above cap 24. A knurled sleeve 27 is screw-seated on the threaded portion 26^a and bears against the upper end of cap 24. The lower end of member 26 extends downwardly between the channel members 17 and terminates in an apertured enlargement 28. The upper ends of a pair of connecting links 29 are pivotally secured to the enlargement 28 by means of a pin or rivet 30. Connecting links 29 extend

downwardly and have their lower ends pivotally connected to the web portion 16^a of expansion member 16 by means of pins or rivets 31, preferably at a point located between the pivotal connections 20 of the spaced pair of links 19.

To insert the base 15 in position in a cylinder, portion 21 is hooked over the wall thereof with the flange portion 16^b bearing against the wall of the cylinder. The weight of the device causes the channel members 17 to drop until the outer edges thereof engage the cylinder wall at points spaced substantially diametrically from flange 16^b, so that the standard is automatically supported within the cylinder. In order to provide more secure anchoring of the base within the cylinder, member 27 is manually operated or turned in proper direction so as to cause rod 26 to be drawn upwardly. This causes, through connection links 29, the expansion member 16 to be forced outwardly, thereby increasing the pressure with which expansion member 16 and channel members 17 engage the cylinder wall.

The arm 11 is fixed at one end to cap member 24 and extends horizontally therefrom and has its outer end terminating in an upwardly presented hook 11^a. Cap member 24 is loosely arranged on the upper end of tubular member 14 so that said cap member can be rotated about the axis of member 14. Thus the arm 11 can be adjusted into any radial position desired.

The supporting means 12 is loosely suspended from said arm 11 and can be moved longitudinally thereof so as to bring the drill and the grinder in any position relative to the standard.

This supporting means consists of a vertically disposed rod 31, a hanger 32, and a coiled tension spring 33. The upper portion 32^a of hanger 32 is bent horizontally and slidably rests on arm 11. The end of said portion is provided with an aperture 34 in which rod 31 is slidably mounted.

The lower portion 32^b of hanger 32 extends downwardly and is deflected inwardly so as to be arranged in close proximity to rod 31. The lower end of said portion 32^b terminates in an upwardly presented hook 35 which is engaged by the upper end of spring 33. This spring surrounds the lower portion of rod 31 and the lower end of said spring engages a downwardly presented hook 36 fixed to said rod near the lower end thereof. Thus said spring forms a resilient supporting connection between the hanger which is suspended from arm 11 and rod 31 from which is suspended the drill B and grinder C. The drill is suspended in position by means of strap A which is attached in any suitable manner to said drill and has a loop portion which engages a hook 37 mounted on the lower end of rod 31. This hook is free to ro-

tate on said rod so that the drill B and grinder C can be rotated without rotating the rod 31.

The engagement between the upper end of spring 33 and hook 35 is preferably effected by having said hook engage a number of coils of said spring. Thus by turning said spring in proper direction the number of turns or coils of said spring engaged by said hook can be increased or decreased as desired so as to increase or decrease the tension of the spring.

Rod 31 extends a suitable distance above portion 32^a and is provided with a stop 38 spaced a suitable distance from said portion. This stop is adjustable on the upper end of said rod and controls the downward stroke of said rod and the grinder C, the purpose being to prevent excessive downward movement of the grinder relatively to the cylinder in which said grinder operates.

Preferably a short section of compression spring 39 is arranged on rod 31 above portion 32^a and this spring forms a shock absorber when the stop 38 is brought downwardly. Hanger 32 is slidably mounted on arm 11 so that the supporting means 12 can be moved longitudinally of said arm. A sufficient clearance exists between rod 31 and the vertical portion of hanger 32 immediately below portion 32^a to permit the supporting means 12 to swing freely in position. This arm 11 is of sufficient length to enable honing operation of all the cylinders in one setting with the exception of the cylinder in which the base is located. The expansion feature of the base is automatic in action, the weight of the device causing the wedging of the base in position in the cylinder, the tension rod 26 and connecting links 29 being used merely to increase the pressure and prevent withdrawal of the standard from the cylinder block.

The expansion foot 15 folds closely against the base 16 and the arm 11 and cap member 24 are detachable from standard 14. Thus the device can be compactly packed for shipment and does not require a great deal of space.

While the supporting means 12 is free to swing in any position desired, it is self-aligning so as to permit the operating unit, and particularly grinder C, to assume coaxial relation with the cylinder in which it operates. The particular arrangement of the supporting means 12 permits it to adjust itself readily to the disposition of the grinder so that there is no tendency during the operation of said grinder to deflect the latter angularly with respect to the vertical axis. This self-aligning feature of the supporting means not only eliminates side pull on the grinding unit but insures efficient and accurate operation of the grinder. It also relieves the workman of the necessity of hold-

ing the grinder to its vertical plane of travel so that his only duty is to move the grinder downwardly into the cylinder against the tension of spring 33, the latter causing the grinder to move upwardly.

The hanger 32 and rod 31 constitute a two-part supporting means for the grinding unit, said parts being yieldably connected together by means of the coiled spring 33. The hanger is arranged on arm 11 and is held against displacement by the upturned outer end 11^a of said arm. The rod 31 is mounted in said hanger and is independent of said arm. Thus by removing the hanger from said arm, the entire supporting means is detached from position.

The base 15 of the device is so constructed that it will fit into any cylinder and is adjustable for different sized cylinders. The expansion member 16 is automatically expanded and the tension member 26 is used to place the base under lateral pressure when in the cylinder and to lock said expansion member 16 in expanded position.

I claim:

1. A device of the class described comprising a vertical standard, a base therefor adapted to be secured within one cylinder of a cylinder block, a horizontal arm pivotally supported at one end on the upper end of said standard and adjustable in a horizontal plane relatively to the axis thereof, a hanger suspended from said arm and movable longitudinally thereof, a rod slidably mounted in said hanger, a tension spring operatively connected at its ends to said hanger and said rod to provide resilient support for the latter, and a hook mounted on the lower end of said rod and adapted to detachably receive and support the grinding unit.

2. A device of the class described comprising a vertical standard, a base therefor adapted to be inserted and secured within a cylinder of a cylinder block, means for expanding said base in said cylinder and render said standard immovable, a member revolvably and coaxially mounted on said standard, a horizontal arm fixed at one end to said member and adjustable therewith radially relatively to the axis of said standard, a two-part supporting means suspended from said arm, one of said parts being supported by said arm and the other part being slidably mounted in the first part, a tension spring anchored at its ends to the respective parts, said spring being adjustable relatively to one of said parts to regulate the tension of said spring, and means carried by said slideable part for detachably receiving and supporting the operating unit.

3. A device of the class described comprising a vertical standard, a base fixed to the lower end of said standard and insertable into a cylinder of a cylinder block and adapted to bear against the cylinder wall thereof

at two spaced points, an expansion member operatively mounted on said base and movable laterally therefrom to engage the cylinder wall at a point spaced from the first mentioned points, a horizontal arm fixed to the upper end of said standard, and supporting means suspended from said arm and resiliently supporting a cylinder grinder and the actuating mechanism therefor whereby said cylinder grinder can be moved in vertical plane.

4. A device of the class described comprising a vertical standard, a base therefor adapted to be inserted into a cylinder of a cylinder block, said base being arranged to engage the cylinder wall at two spaced points, a plurality of links pivotally connected at one of their ends to said base and extending laterally therefrom, an expansion member pivotally connected to the outer ends of said links and movable in parallelism to said base, said member being expandable to engage the cylinder wall at points spaced from the first mentioned points, means for locking said expansion member in expanded position, and means for adjustably and resiliently supporting an operating unit from the upper end of said standard.

5. A device of the class described comprising a vertical standard, a pair of channel members having their upper ends converging and secured to the lower end of said standard and having their lower ends arranged in spaced parallel relation, a series of horizontally disposed rods secured to and extending between said spaced parallel portions, a plurality of links pivotally mounted at one of their ends on said rods and extending outwardly therefrom, an expansion member arranged in parallel relation with and operable in a plane central to said spaced parallel portions, said expansion member being pivotally connected to the outer ends of said links, the upper end of said expansion member being provided with a hook portion for engaging the top of the cylinder block whereby upon the insertion of the base within the cylinder and the engagement of the upper end of said expansion member with the top of the cylinder block said expansion member and said base are automatically moved away from each other and into engagement with the cylinder wall at a plurality of points, a horizontal arm movably mounted at one end on the upper end of said standard and adjustable in a horizontal plane about the axis thereof, means adjustably mounted on said arm for resiliently supporting the operating unit above said cylinder block, and a manually adjustable member operatively connected to said expansion member for locking the latter in expanded position.

6. A device of the class described comprising in combination with a standard, a pair of base members arranged in spaced vertical relation and having their upper ends converging and secured to the lower end of said standard, a series of pins transversely disposed between said base members, a plurality of links arranged in pairs and having one of their ends pivotally mounted on said pins, an expansion member arranged in spaced parallel relation with said base members and pivotally connected to the outer ends of said links whereby said expansion member is movable outwardly in parallelism with said base members, and a lateral outwardly presented projection on the upper end of said expansion member for engaging the top of a cylinder when the base structure is inserted thereinto whereby the base members and said expansion member are automatically expanded laterally relatively to each other to engage the cylinder wall at a plurality of spaced points.

7. A device of the class described comprising in combination with a standard, a pair of base members arranged in spaced vertical relation and having their upper ends converging and secured to the lower end of said standard, a series of pins transversely disposed between said base members, a plurality of links arranged in pairs and having one of their ends pivotally mounted on said pins, an expansion member arranged in spaced parallel relation with said base members and pivotally connected to the outer ends of said links whereby said expansion member is movable outwardly in parallelism with said base members, a lateral outwardly presented projection

tally disposed rods secured to and extending between said spaced parallel portions, a plurality of links pivotally mounted at one of their ends on said rods and extending outwardly therefrom, an expansion member arranged in parallel relation with and operable in a plane central to said spaced parallel portions, said expansion member being pivotally connected to the outer ends of said links, the upper end of said expansion member being provided with a hook portion for engaging the top of the cylinder block whereby upon the insertion of the base within the cylinder and the engagement of the upper end of said expansion member with the top of the cylinder block said expansion member and said base are automatically moved away from each other and into engagement with the cylinder wall at a plurality of points, a horizontal arm movably mounted at one end on the upper end of said standard and adjustable in a horizontal plane about the axis thereof, means adjustably mounted on said arm for resiliently supporting the operating unit above said cylinder block, and a manually adjustable member operatively connected to said expansion member for locking the latter in expanded position.

8. A device of the class described comprising in combination with a standard, a pair of base members arranged in spaced vertical relation and having their upper ends converging and secured to the lower end of said standard, a series of pins transversely disposed between said base members, a plurality of links arranged in pairs and having one of their ends pivotally mounted on said pins, an expansion member arranged in spaced parallel relation with said base members and pivotally connected to the outer ends of said links whereby said expansion member is movable outwardly in parallelism with said base members, and a lateral outwardly presented projection on the upper end of said expansion member for engaging the top of a cylinder when the base structure is inserted thereinto whereby the base members and said expansion member are automatically expanded laterally relatively to each other to engage the cylinder wall at a plurality of spaced points.

9. A device of the class described comprising in combination with a standard, a pair of base members arranged in spaced vertical relation and having their upper ends converging and secured to the lower end of said standard, a series of pins transversely disposed between said base members, a plurality of links arranged in pairs and having one of their ends pivotally mounted on said pins, an expansion member arranged in spaced parallel relation with said base members and pivotally connected to the outer ends of said links whereby said expansion member is movable outwardly in parallelism with said base members, a lateral outwardly presented projection

on the upper end of said expansion member for engaging the top of a cylinder when the base structure is inserted thereinto whereby the base members and said expansion member are automatically expanded laterally relatively to each other to engage the cylinder wall at a plurality of spaced points, and a manually operable member cooperating with said standard and operatively connected to said expansion member to lock the latter in expanded position.

9. A device of the class described comprising in combination with a standard, a pair of base members arranged in spaced vertical relation and having their upper ends converging and secured to the lower end of said standard, a series of pins transversely disposed between said base members, a plurality of links arranged in pairs and having one of their ends pivotally mounted on said pins, an expansion member arranged in spaced parallel relation with said base members and pivotally connected to the outer ends of said links whereby said expansion member is movable outwardly in parallelism with said base members, a lateral outwardly presented projection on the upper end of said expansion member for engaging the top of a cylinder when the base structure is inserted thereinto whereby the base members and said expansion member are automatically expanded laterally relatively to each other to engage the cylinder wall at a plurality of spaced points, a tension rod extending upwardly through said standard, a link pivotally connecting the lower end of said rod with said expansion member, and manually operable means cooperating with said standard and with said tension rod for drawing the latter upwardly to lock said expansion member in position.

10. In a device of the class described, the combination with a standard and an arm extending radially therefrom, of a hanger disposed to one side of said arm and having its upper end slidably resting thereon and provided with a vertically disposed aperture arranged on the other side of said arm, a vertically disposed rod slidably mounted in said aperture and extending downwardly below said hanger, means for detachably supporting a grinding unit on the lower end of said rod, and a coiled spring on said rod and attached at its upper end to the lower end of said hanger and at its lower end to said rod whereby the latter is resiliently supported by said hanger and movable in a vertical plane.

11. In a grinding support of the class described, a hanger member having its upper end slidably adapted to engage a support arm and to be freely suspended therefrom, a vertically disposed slidable member mounted in said hanger member to one side of said support arm, a coiled spring secured at one end to said hanger below said support arm

and having the other end secured to said slidable member whereby the latter is resiliently supported on said hanger member and is movable in a vertical plane relatively thereto, said spring being adjustable relatively to one of said members so as to increase or decrease the tension of said spring, and a hook mounted on the lower end of said slidable member and rotatable about a vertical axis and adapted to have detachably secured thereto the grinding unit.

12. A portable grinder stand having a base adapted for insertion into a cylinder, said base comprising a pair of supporting elements, spaced links connecting said elements in movable, parallel relation, and a standard carried by and projecting upwardly from one of said supporting elements.

13. An engine cylinder grinder stand comprising a pair of supporting elements, links connecting said elements in movable, spaced relation, means for holding one of said elements in relatively fixed position with respect to the cylinder, a standard carried by the other element, said links being arranged to move the standard carrying element into engagement with the cylinder wall on exerting force downwardly on said element.

14. A portable grinder stand having a base adapted for insertion into a cylinder, said base comprising a pair of supporting elements, means connecting said elements and adapted to force them apart on exerting force downwardly on one of them.

In testimony whereof I hereunto affix my signature this 25th day of June, 1930.
